UNITED STATES PATENT OFFICE.

EDWARD L. KELLAN, OF CHICAGO, ILLINOIS.

VALVE FOR BUBBLING FOUNTAINS.

1,071,753.

Specification of Letters Patent.

Patented Sept. 2, 1913.

Application filed August 11, 1911. Serial No. 645,289.

To all whom it may concern:

Be it known that I, EDWARD L. KELLAN, a citizen of the United States, and a resident of Chicago, in the county of Cook and State of Illinois, have invented certain new and useful Improvements in Valves for Bubbling Fountains; and I do hereby declare that the following is a full, clear, and exact description thereof, reference being had to the accompanying drawings, and to the characters of reference marked thereon, which form a part of this specification.

This invention relates to an improved valve for sanitary bubbling fountains and for other uses.

Among the objects of the invention is to provide a valve device of this character which may be readily manipulated and is adjustable to vary the flow of water therethrough to correspond with the pressure or head of the water so as to produce the desired flow at the bowl or cup of the fountain, when embodied in such a fountain.

Other objects of the invention are to provide an improved valve for this and like purposes which is simple in construction, which may be easily operated, and to produce a valve the parts of which are protected from unauthorized access to thereby prevent tampering with the valve by unauthorized persons.

The invention consists in the matters hereinafter set forth and more particularly pointed out in the appended claims.

Figure 1 is an axial section, with parts in elevation, of a bubbling fountain embodying my improvements. Fig. 2 is a section of the valve mechanism with the parts shown in changed positions. Fig. 3 is a plan view of the cup or bowl of the fountain.

As shown in the drawings, 10 designates a hollow, horizontally arranged shank for the cup 11 of the fountain, said cup having an upwardly shaped bell or flaring mouth 12, the margin of which is widened to produce a wide rim. The widening of the rim or flange 14 of the cup is advantageous inasmuch as it avoids a sharp edge at this point against which the face of a person using the fountain may be pressed or forced in a manner to injure the same. The lower end of said cup is internally screw-threaded at 15 and fits over and has screw-threaded engagement with an exteriorly screw-threaded

nipple or flange 16 near the outer end of the shank 10. The inner end 18 of said shank is formed to provide a casing to enclose the valve mechanism for the fountain, and said casing may be provided with the nipple 19, 20, which may be arranged at right angles, as shown, to each other, one adapted for connection with a water supply pipe and the other with a draw off valve 21. The two nipples or extensions 19 and 20 are provided to permit the device to be connected to either a horizontal or a vertical pipe, and when so constructed the draw off valve 21 may be conveniently connected to the nipple that is not connected to the supply pipe. At the bottom of the rear end of the hollow shank 10, which rear end is closed, is a vertical opening 22, around the lower side of which may be formed a valve seat 23, the wall of said opening being of substantial depth.

24 designates a hollow valve piece which fits closely within the opening 22 and is provided at its lower end with a reduced screw-threaded portion 26 which extends into the nipple 20. Upon said reduced screw-threaded portion 26 is fitted a washer 27 to constitute a valve seat to engage the seat 23, as best shown in Fig. 2 (the latter figure showing the valve in its closed position). Said seat washer is held pressed against a downwardly facing shoulder of the valve piece 24 by means of a nut 28 which is locked in place by the lock nut 29.

The valve piece is provided with an upwardly extending tubular stem 31 which extends through an opening in the upper wall of the shank that is in line with the valve opening 22, and said stem extends into a tubular bonnet 32 made integral with said shank. The said stem is externally screw-threaded at its upper end to receive the internally screw-threaded member 33 of a cap 34 which has an annular flange portion 35 that fits over and has close sliding engagement with the upper end of the bonnet 32. A water tight joint is formed between the said valve stem and the upper wall of the shank 10 by means of a packing or gland consisting of a body of packing material 37 which is interposed between the upper conically shaped wall of the shank 10 and a follower ring 38 surrounding the stem, said follower ring being pressed upon the packing material and the packing ma-

- material thereby compressed by means of a spiral expansion spring 40 which is interposed between the cap 34 and follower ring 38.
- 5 The valve piece 24 is provided with two pairs of vertically separated inlet and outlet ports 42, 43, the ports of each pair communicating with the hollow interior 44 of the valve piece and extending in opposite 10 directions therefrom as herein shown.
- 10 When the valve piece is in its upper position, in which position it is held by the spring 40, (Fig. 2) the oppositely extending inlet ports 42 are held above the opening 22 15 in which the valve piece closely fits, and the valve ring or washer 27 is pressed closely against its seat 23, so that at this time no water is allowed to flow through the valve device to the interior of the hollow shank 20 20 of the fountain. When the valve is depressed to the position shown in Fig. 1, the lower or inlet ports 42 are thereby brought beneath the valve seat, and the valve ring or washer 27 is removed from said seat, so 25 that at this time the said inlet ports are open to the pressure or head of the water supply. The water is free to flow, therefore, through the inlet ports and the bore of the valve piece 44, and is discharged 30 through the outlet ports 43 into the rear end of the hollow shank through which it passes to the cup in a manner hereinafter described.
- In order to regulate the flow of water 35 through the valve and to cut down the initial volume at the receiving side of the valve to that required at the cup of the fountain, I may provide a regulating device which is made as follows: 46 designates a short rod 40 which is contained within the hollow stem of the valve piece and extends at its lower end downwardly into the bore 44 of said valve piece. Said rod is screw-threaded at its lower end, as indicated at 47, to engage 45 internal screw threads in the upper end of the bore of the valve piece above the outlet ports 43. By turning said rod thus screw-threaded to the valve piece downwardly toward the outlet ports 43, the area of said 50 ports may be restricted more or less to correspondingly restrict the flow of water through said ports and the pressure at which the water issues from said ports. The said regulating rod may thus be turned to regulate 55 the pressure by means of a suitable implement applied to a slot 48 at the upper end of the rod, and near the upper end of the valve piece stem. In this manner I am able to restrict the outlet ports and vary the volume of water passing therefrom and correspondingly vary the pressure without disturbing the operating members of the valve mechanism, and without therefore cutting off the flow of water through the valve.
- 60 65 As herein shown the upper end of the valve stem is closed and the notched or grooved end of the regulating rod is protected by means of a knob 50 which is internally screw-threaded to engage over the exterior screw threads of the stem, as best shown in Fig. 2. The knob 50 constitutes, in addition to the functions described, a lock nut by which to securely lock the cap 34 on the valve piece stem. In order to prevent water escaping around the regulating rod, I 70 may provide the same with a shallow groove 52 (Fig. 2) in which to place an annular packing 53 of any suitable material that fits closely within the hollow valve piece stem. 75
- As herein shown the draw off valve 21 is 80 provided with an externally threaded tubular extension or nipple 54 which is adapted to fit into either one of the internally screw-threaded projections 19 or 20, depending upon to which projection the water supply 85 pipe is connected. When said draw off valve 21 is employed the lower extension 26 of the valve piece may be provided with a passage 56 which is in open communication with the high pressure side of the valve when the 90 valve piece is depressed, as shown in Fig. 1, so that water may be at such time drawn from the device through the valve 21, as when it is desired to draw a glass of water from the device. When the valve piece 24 95 occupies its upper or normal position water under the initial pressure of the system from which the water is supplied is free to pass directly to the draw off valve 21.
- As herein shown the supporting member 100 or shank 10 of the fountain is formed with a central, longitudinal diaphragm 60 to provide an upper passage 61 through which the water is conducted from the cut off valve to the cup. Said diaphragm also provides at 105 the lower side of the shank a waste passage which receives water from a waste opening 63 at the bottom of the cup and conducts it to an outlet or waste nipple 64 at the rear of the supporting member or shank. The 110 said nipple 64 may be screw-threaded to receive a waste pipe, or the water may flow therefrom into a receptacle beneath the same. The passage 61 terminates centrally within the cup in an upstanding tubular member 66, and which is shown as provided 115 with a detachably fitted terminal 67 which extends a distance upwardly from the bottom of the cup. Said terminal is shown as fitted within and is screw-threaded to the 120 upstanding tubular member 66.
- The relation of the areas of the outlet ports 43 of the valve piece and of the passage 61, in connection with the manner of varying the pressure of the water as it enters the passage 61, is such that the water 125 may be made to rise into the cup 11 to the proper height without overflowing the sides of the cup while at the same time maintaining the terminal 67 of the water supply 130

passage sufficiently low in the cup to prevent contact with the lips or the teeth of the person drinking from the fountain.

In order to produce and maintain a sufficiently rapid flow of the waste water away from the device, I may provide the diaphragm 60, at or near the waste opening 64, with a small opening 65 through which the water may flow in a jet directly from the passage 61 to the rear end of the waste passage 62. The jet of water is thus forced across the outlet nipple and across the stream of water which escapes from the waste passage, with the effect to keep the outlet nipple filled with water. Therefore when the outlet opening 63 at the bottom of the cup is filled, as it normally is, the water leg beneath the outlet nipple serves to produce a siphonic action or pull on the stream of waste water which will insure a rapid drain of waste water therefrom. The outer end of the waste passage 62 is preferably provided with an opening that is closed by a plug 70, upon removal of which a suitable implement may be inserted into the waste passage to clean the same of any matter which may accumulate therein. In case the diaphragm 60 be omitted and the hollow member 10 constitutes only the supply pipe to the drinking cup, the drain water may pass directly from the cup through drain openings at the bottom of the cup and be discharged into a receptacle placed beneath the same.

35 I claim as my invention:—

1. A valve comprising, in combination with a hollow outlet member adapted for communication at its inlet end with a source supplying fluid under pressure, said member being provided at its inlet end with an opening surrounded by a body seat, a hollow valve piece slidable in said opening and provided with a seat member to engage said body seat and above said seat member with vertically separated inlet and outlet ports communicating with the hollow interior of the valve piece, said valve piece being provided with a hollow stem, a bonnet connected with the hollow member through which said stem extends, a cap slidable on the outer end of the bonnet and connected to said stem, a spring within the bonnet and acting on said cap to normally hold the valve piece seat member engaged with the body seat and to maintain the inlet port of the valve piece above said body seat.

2. A valve comprising, in combination with a hollow outlet member adapted for communication at its inlet end with a source supplying fluid under pressure, said member being provided at its inlet end with an opening surrounded by a body seat, a hollow valve piece slidable in said opening and provided with a seat member to engage said body seat and above said seat member with

vertically separated inlet and outlet ports communicating with the hollow interior of the valve piece, said valve piece being provided with a hollow stem, a bonnet connected with the hollow member through which said stem extends, a cap slidable on the outer end of the bonnet and connected to said stem, a spring within the bonnet and acting on said cap to normally hold the valve piece seat member engaged with the body seat and to maintain the inlet port of the valve piece above said body seat; and a rod contained within said hollow stem and screw-threaded thereto and extending at its lower end to the outlet port of the valve piece and adapted by rotative movement of the rod to cut off more or less of said outlet port, said rod being exposed at its upper end through the upper end of the hollow valve stem.

3. A valve comprising, in combination with a hollow outlet member adapted for communication at its inlet end with a source supplying fluid under pressure, said member being provided at its inlet end with an opening surrounded by a body seat, a hollow valve piece slidable in said opening and provided with a seat member to engage said body seat and above said seat member with vertically separated inlet and outlet ports communicating with the hollow interior of the valve piece, said valve piece being provided with a hollow stem, a bonnet connected with the hollow member through which said stem extends, a cap slidable on the outer end of the bonnet and connected to said stem, a spring within the bonnet and acting on said cap to normally hold the valve piece seat member engaged with the body seat and to maintain the inlet port of the valve piece above said body seat, a rod contained within said hollow stem and screw-threaded thereto and extending at its lower end to the outlet port of the valve piece and adapted by rotative movement of the rod to cut off more or less of said outlet port, said rod being exposed at its upper end through the upper end of the hollow valve stem, and said rod being provided with an annular recess and a packing in said recess closely fitting said hollow stem.

4. A valve comprising, in combination with a hollow outlet member adapted for communication at its inlet end with a source supplying fluid under pressure, said member being provided at its inlet end with an opening surrounded by a body seat, a hollow valve piece slidable in said opening and provided with a seat member to engage said body seat and above said seat member with vertically separated inlet and outlet ports communicating with the hollow interior of the valve piece, said valve piece being provided with a hollow stem, a bonnet connected with the hollow member through

which said stem extends, a cap slidable on the outer end of the bonnet and connected to said stem and a spring within the bonnet and acting on said cap to normally hold the 5 valve piece seat member engaged with the body seat and to maintain the inlet port of the valve piece above said body seat, a rod contained within said hollow stem and screw-threaded thereto and extending at its 10 lower end to the outlet port of the valve piece and adapted by rotative movement of the rod to cut off more or less of said outlet port, said rod being exposed at its upper end through the upper end of the hollow 15 valve stem, and a member secured to the upper open end of said stem for closing the upper end of said rod.

5. A valve comprising, in combination with a hollow outlet member adapted for 20 communication at its inlet end with a source supplying fluid under pressure, said member being provided at its inlet end with an opening surrounded at one side by a body seat, a hollow valve piece having a hollow 25 stem and slidable in said opening and provided with a seat member to engage said body seat, and provided above said seat member with vertically separated inlet and outlet ports communicating with the hollow 30 interior of the valve piece, a bonnet connected to the hollow member through which said hollow stem extends, a cap screw-threaded to the outer end of the hollow stem and slidable on the outer end of the 35 bonnet, a spring acting on the cap to normally hold the valve piece seat member engaged with the body seat and to maintain the inlet port of the valve piece above said body seat, a rod movable endwise in said 40 hollow stem and adapted to extend to, and by its endwise movement restrict the flow of liquid through, said outlet port, said rod being exposed at its upper end through the upper end of the hollow stem, and a 45 knob screw-threaded to the upper end of the stem to close the same and to constitute a lock nut to hold said cap to the stem.

6. In a valve, a member provided with an opening surrounded by a body seat disposed 50 in a plane transverse to the axis of said opening, and with an outlet passage, a hollow valve piece slidable in said opening and having a seating face transverse to its axis to engage the body seat and provided with 55 a hollow stem, and with separated inlet and outlet ports communicating with the interior of the valve piece, a spring acting on the stem to normally hold the valve piece

against said body seat and a regulating rod movable in said stem and hollow valve piece 60 to restrict the flow of fluid through the outlet port, with means for giving movement to said rod.

7. A valve for the purpose set forth, comprising a member provided with an opening surrounded at one side by a body seat, a hollow valve piece provided with a hollow stem and slidable in said opening and provided with a seating member to engage the body seat and above said seating member 70 with vertically separated inlet and outlet ports in communication with the interior of the valve piece, a bonnet outwardly through which said hollow stem extends, a cap slid- 75 able on the outer end of the bonnet and affixed to said stem, a packing device surrounding the stem within the bonnet, a spring interposed between said packing device and said cap, and a regulating member movable in said hollow stem and valve piece 80 to restrict the flow of fluid through said outlet port.

8. A valve for the purpose set forth, comprising a member provided with an opening surrounded at one side by a body seat, a hollow valve piece provided with a hollow stem and slidable in said opening and provided with a seating member to engage the body seat and above said seating member with vertically separated inlet and outlet 90 ports in communication with the interior of the valve piece, a bonnet outwardly through which said hollow stem extends, a cap screw-threaded to the outer end of said stem and slidable on the outer end of said 95 bonnet, a packing device surrounding the stem within the bonnet, a spring interposed between said packing device and said cap, a regulating member movable within said hollow stem and valve piece to regulate the 100 flow of fluid through said outlet port, said regulating member being exposed through the outer end of the hollow valve piece stem and a member screw-threaded to the outer end of said stem to close the same and 105 to constitute a lock nut to lock the cap to the valve piece stem.

In testimony, that I claim the foregoing as my invention I affix my signature in the presence of two witnesses, this 10th day of 110 August A. D. 1911.

EDWARD L. KELLAN.
